HARRY H. STYLL, OF SOUTHBRIDGE, MASSACHUSETTS.

OPHTHALMIC MOUNTING.

1,202,240.

Specification of Letters Patent.

Patented Oct. 24, 1916.

Application filed July 24, 1915. Serial No. 41,748.

To all whom it may concern:

Be it known that I, HARRY H. STYLL, a citizen of the United States, residing at Southbridge, in the county of Worcester and 5 State of Massachusetts, have invented certain new and useful Improvements in Ophthalmic Mountings, of which the following is a specification.

This invention relates to ophthalmic 10 mountings and has particular reference to improvements in lens engaging members or clips.

The primary object of the invention is to provide an adjustable clip of this character, 15 whereby it may be readily and easily applied to lenses having varying curves and thicknesses.

Another object of the invention is to provide a clip of this character which will be 20 positively held against accidental loosening from the lens in contra-distinction to being merely secured thereto through the medium of the adhesive properties of the cement or other uniting material.

25 A further object of the invention is to provide an adjustable clip of this character in which the ears will firmly engage with the lens throughout their lens engaging area, irrespective of the curve or thickness of the 30 lens, thereby providing for a firm, secure and efficient connection between the lens and clip, and providing a mounting which is neat in appearance.

A still further object of the invention is to 35 provide a novel form of lens, when the same is of greater thickness than the maximum adjusted width of the clip, whereby the clip may be readily applied thereto.

With the foregoing, the invention consists 40 in the novel features of construction, combination and arrangements of parts, as will be hereinafter more fully described, illustrated in the accompanying drawings and claimed.

In the drawings: Figure I is a fragmentary face view of a lens and clip constructed in accordance with the invention. Fig. II is a fragmentary perspective view of a portion of the lens. Fig. III is a horizontal sectional view taken centrally through the lens and clip, as shown in Fig. I of the drawing. Fig. IV is a similar view of a slightly modified form of clip. Fig. V is a similar view of another slightly modified form of clip. Fig. VI is a similar view of still another modified 50 form of clip. Fig. VII is a similar view of the clips shown in Fig. III of the drawing,

showing the same as applied to a lens as illustrated in Fig. II of the drawing. Fig. VIII is a detailed perspective view of the clip shown in Figs. III and VII of the drawing. Fig. IX is a view similar to Fig. IV, showing the application of this form of clip to another form of my improved lens. Fig. X is a horizontal sectional view taken centrally through another modified form of clip. Fig. XI is a sectional view of still another modified form of clip.

Referring to the drawings by numerals, 1 designates a lens which may be of any thickness, and which may be ground to any 70 design curved, while 2 designates a clip for attachment thereto.

As previously mentioned it is the object of the invention to enable a cementitiously fastened lens clip to be applied to a lens 75 irrespective of the thickness or curve of the lens. In Figs. I to X inclusive, and in Fig. XI of the drawings I have illustrated at least one of the ears of the clip as being adjustable relative to the remaining ear, and 80 have shown the ears as being connected by an extensible or compressible web, but in some instances, as in Figs. III, VI, and X, I have shown both the ears as being adjustable. The clip is adapted to be applied to a lens having 85 a slot formed in one edge thereof to receive the web, and the same is preferably secured to the lens through the medium of a suitable cement, or like material, and the ears of the clip may be made adjustable to permit of 90 their application to lenses having varying curves and thicknesses. By the use of a construction such as has been referred to it will be seen that the ears of the clip may be readily spread apart or crushed together to 95 fit lenses of various thickness, and that the same may be readily adjusted so as to lie in firm engagement with the faces of the lens irrespective of the curve ground thereon.

In Figs. I, III and VIII of the drawings I 100 have shown one preferred embodiment of my invention, in which the clip 2 comprises a strap portion 3, ears 4 and a pair of adjustable web portions 5, slots 6 being formed in the strap 3, so that the ears may be readily 105 forced apart to permit of the clip being applied to lenses having thick edges. The lens to which this clip is to be applied has a slot 7 to receive the web 5 and the uniting medium, such as cement or the like. It will be noted 110 that should the lens be of a concave or convex form, or in fact, any curve whatever, the

ears 4 may be readily adjusted so as to fit neatly against the curve faces thereof, and it will be further noted that both of the ears of the clip are adjustable, so that both of the 5 ears may be adjusted to fit the respective faces of the lens.

In Fig. IV of the drawings I have illustrated substantially the same construction as set forth in connection with the showing in 10 Fig. III of the drawing, but in this instance I have provided one of the ears rigid with the strap portion, and have made the other ear adjustable. This clip is especially adapted for use upon lenses having one plane surface.

In Fig. V of the drawings the form of the clip illustrated is substantially the same as that shown in Fig. IV, with the exception that instead of providing a pair of adjustable connecting webs for the ears, but a 20 single web is provided, which extends diagonally across the intervening space between the ears and is adapted to be adjusted in a manner similar to the adjustment of the webs shown in Figs. III and IV of the drawing.

In Fig. VI, I have illustrated another embodiment of my invention, in which the ears 4' are both made adjustable relative to the strap portion 3' by forming these ears separately from the strap portion and connecting the same with the strap by means of the web 8, and if desired a second web 9 may be provided in order to firmly connect the same and prevent their accidental loosening from the lens.

One important advantage gained by the structures and mode of fastening just described is that the cement is placed about the web so that the webs are embedded therein, 40 whereby when the same hardens it will prevent any movement of the web, which consequently prevents any movement of the clip ears, and thus positive means are provided for preventing accidental breaking away of 45 the clip ears, as has heretofore been common, when only the adhesive properties of the cement were utilized to secure the clip to the lens.

Where a lens is extremely thick, and the 50 degree of adjustment of the improved strap is insufficient to accommodate the same recesses 10 may be formed in either or both faces of the lens adjacent to slot 7, so as to permit the clips to be readily applied thereto. In Fig. VII of the drawings I have illustrated a lens as having both faces thereof provided with the recesses 10, and have shown the form of clip illustrated in Fig. III, as being applied thereto.

60 In Fig. IX of the drawings I have illustrated the manner in which the form of clip shown in Fig. IV may be applied to a thick lens having double convex surfaces. In this instance a recess 11 is formed in one face of 65 the lens, and the rigid clip ear is arranged

therein, while the adjustable clip ear is adjusted to fit the curved face of the lens, as is clearly shown.

In Fig. X of the drawings the ears of the 70 clip are shown as being separate from the strap portion, and as being connected thereto by means of the web 12 which is formed on the strap, and which has adjustable fingers secured to the ears, inturned flanges 13 being formed on the ears and extended 75 over the outer face of the strap in order that no portion of the edge of the lens will be exposed when the ears are adjusted away from each other.

In Fig. XI of the drawings I have illustrated another slightly modified form of my invention, in which one rigid clip ear is provided which is connected to an adjustable clip ear by means of the angularly shaped web portion 5'. In this form of my invention as should be apparent by reference to the drawings, when it is desired to widen the clip to receive a thicker lens it is merely necessary to insert a pair of pliers in the mounting pressing against the central corners or points of the diamond formed by the two cross arms or web when tightening of the pliers will serve to force the two ears apart in the manner of operation of a toggle joint. On the other hand, if it is desired to fit the strap to a thin lens, pressure on the outside of the strap portion will compress the web which will then open out into a more nearly square in place of diamond shaped figure. It is to be understood that these 90 arms are preferably of material sufficiently rigid to satisfactorily hold the ears in desired adjusted position under ordinary service conditions, while permitting of manipulation of the mounting by the use of pliers or the like, as has just been described.

When the mounting is actually placed in use, however, the cement or other connecting medium 17 is placed in position when in a soft or plastic condition, and as is illustrated in the various figures of the drawing this cement fills all the space in the slot in the lens and surrounds the members 5, 5' or the like, and when it has been allowed to set 100 hardens therearound in the same manner that concrete hardens around a metal reinforcement or strap, and this hardening serves to secure the ears in exactly desired adjusted position, since to shift them either closer together or farther apart it is necessary to crush the hardened cement or connecting medium 17. Consequently the ears are mechanically locked by this material in the desired relatively adjusted position irrespective of the adhesive properties of the 110 material sticking to the faces of the metallic strap and holding the parts thereof in position. In this connection particular attention is also invited to the manner in which the strap or clip is retained in position, in that 120

the slotted portion of the lens presents not the smooth polished exterior surface, but a rough and porous surface into which the cement will run to a certain degree when in 5 its heated or plastic condition and with which the cement may obtain an extremely secure hold, while the fact that this cement in a continuous body extends around and has embedded therein the cross pieces 5, 5' or the like firmly and securely unites the clip with 10 the lens by the mechanical formation of the hardened connecting medium irrespective of its adhesive property, it being preferable, however, that the material have considerable 15 adhesive properties to serve both as a binder through the apertures between the web to hold the two separated portions or opposite sides of the slot together and reinforce the same, and also to better retain the lens and 20 clip in engagement. Especial attention is also invited to the shape of the clip ears, as is clearly illustrated in Figs. I and VIII, from which it will be noted that the strap ear is of slender outwardly convex material so 25 shaped that the rounding of the material will cause a high light on the central portion and will to a certain degree obscure the edge portion and thus render the strap considerably less conspicuous and more ornamental in appearance than is the customary 30 flat or similar strap now in general use.

From the foregoing it will be seen that I have provided an improved clip embodying independent and relatively adjustable ears, 35 which clip may be advantageously secured to varying thicknesses of lenses by cement or the like, which will present an extremely neat and attractive appearance and in which the parts will be so braced and locked in the 40 presence of the cement as to prevent any accidental shifting thereof from desired adjustable position while permitting of adjustment thereof to fit the lens in the absence of the cement or connecting medium, and it 45 will be understood that I may make any

modifications in the specific details of construction shown and described within the scope of the appended claims without departing from or exceeding the spirit of my invention.

50

I claim:

1. A lens attachment for an ophthalmic mounting comprising a strap portion and a clip ear, and a second free or loose clip ear unattached to the strap, and a pair of bowed 55 web or connecting members secured to and connecting the two clip ears to permit of relative adjustment of the clip ears and of movement of the free clip ear relative to the strap by increasing or decreasing the amount 60 of bowing of the connecting webs.

2. A lens attachment for an ophthalmic mounting comprising a strap portion and a clip ear, and a second free or loose clip ear unattached to the strap and a web or connecting member rigidly secured at each end to one of the clip ears and greater in length than the direct distance between the clip ears to permit of relative adjustment of the 65 clip ears by bending of said web member. 70

3. In a mounting of the character described, including a pair of clip ears, a pair of bowed or bent web members rigidly secured at their ends to the clip ears to prevent rocking or twisting movement of the 75 ears relative to the webs, said webs being adapted to engage and be locked in adjusted position by a cementitious filler, a strap member, and a neck uniting the strap member with at least one of the web members, at 80 least one of the clip ears being free from connection with the strap member except through the medium of the neck and one of the web members just referred to.

In testimony whereof I affix my signature 85 in the presence of two witnesses.

HARRY H. STYLL.
